(57) **CLAIM**

The ornamental design for an ankle brace as shown and described.

DESCRIPTION

FIG. 1 is a perspective view of my new design in an ankle brace for the right ankle;

FIG. 2 is a right (outside) elevation view of my new design in the brace of FIG. 1;

FIG. 3 is a front elevation view of my new design in the brace of FIG. 1;

FIG. 4 is a left (inside) elevation view of my new design in the brace of FIG. 1;

FIG. 5 is a rear elevation view of my new design in the brace of FIG. 1;

FIG. 6 is a top plan view of my new design in the brace of FIG. 1;

FIG. 7 is a bottom plan view of my new design in the brace of FIG. 1;

FIG. 8 is a perspective view of my new design in an ankle brace for the left ankle;

FIG. 9 is a left (outside) elevation view of my new design in the brace of FIG. 8;

FIG. 10 is a front elevation view of my new design in the brace of FIG. 8;

FIG. 11 is a right (inside) elevation view of my new design in the brace of FIG. 8;

FIG. 12 is a rear elevation view of my new design in the brace of FIG. 8;

FIG. 13 is a top plan view of my new design in the brace of FIG. 8; and,

FIG. 14 is a bottom plan view of my new design in the brace of FIG. 8.

The closely-spaced dashed lines on claimed surfaces depict stitching and form no part of the claim. The dashed lines depicting the outline of a person's foot and ankle bearing the ankle brace form no part of the claim

1 Claim, 14 Drawing Sheets
